PETER M. COLQUHOUN, OF CLEVELAND, OHIO, ASSIGNOR TO THE AMERICAN MULTIGRAPH COMPANY, OF CLEVELAND, OHIO, A CORPORATION OF OHIO.

CONTROLLING DEVICE FOR THE KEYS OF KEYBOARD MACHINES.

Application filed March 9, 1925. Serial No. 14,118.

Application No. 535,311, filed February 9, 1922 by Clifton Chisholm for an embossing machine which has matured into Patent 1,557,754 dated Oct. 20, 1925 shows, describes and claims a machine for embossing a row of characters upon a printing strip or ribbon comprising a reciprocating die head having male and female dies facing each other on opposite sides of the ribbon, a keyboard to control the position of the die head, a plunger mechanism operating automatically when the die head comes to position to force the selected dies toward each other to emboss the ribbon. The keys are arranged in two banks, and each key of a bank is adapted to energize a mechanism associated with that bank and serving to move the die head from a central neutral position in one direction until it is stopped by engaging the raised rear end of the depressed key lever. Consequent upon such engagement the automatic mechanism is initiated which plunges the dies toward each other.

Means is provided in the Chisholm machine to prevent the depression of a subsequent key until the preceding key has been released and returned to normal position, but it has been found that occasionally after the embossing operation is completed, and the depressed key returned, the operator will strike a second key in the same bank before the die head has had time to return to neutral position, with the result that the die head is stopped on the return stroke instead of on a second outward stroke and that the wrong character is embossed. This result happens especially when the first key struck is one which gives the die carrier nearly its extreme movement and the second key happens to be one which would give the die carrier only a short movement, that is to say where there is considerable space interval between the rear end of the first depressed key and that of the second key, and even then it only happens when the operator is actuating the keys in the same bank in very rapid succession.

The difficulty mentioned may be avoided by care on the part of the operator, but a speedier operation may be obtained if the operator does not have to pay attention to this contingency. It is the object of the present invention to provide mechanism to positively prevent the actuation of a second

key in the same bank until the die head has returned to its neutral position.

The present invention provides means preventing the actuation not only of a subsequent character key in the same bank, but also of the space key until the die head is returned to neutral position. In the Chisholm machine, the space key, while it does not operate to shift the die head, does operate the plunger mechanism, because the ribbon feeding mechanism is coupled therewith, and hence the space key, if operated too quickly after a positioning key may cause the plungers to engage dies as the die head is returning instead of operating in a vacant space at the center of the die head. The peculiarity of the Chisholm space key mechanism requires a different mechanism for preventing this actuation from that of a character key and the present invention provides such different mechanism.

My invention is illustrated in the drawings hereof and is hereinafter more fully explained. Its essential characteristics, however, which are set out in the claims, are not intended to be limited to the specific mechanisms shown.

In the drawings, Fig. 1 is a sectional side elevation of so much of an embossing machine of the Chisholm type as is concerned with the present invention, this view showing also my safety mechanism; Fig. 2 is a section plan indicated by the line 2—2 on Fig. 1 of the relevant portion of the embossing machine shown in Fig. 1; Fig. 3 is a vertical cross-section of the offset planes indicated by the lines 3—3 in Figs. 1 and 2 looking toward the rear; Fig. 4 is a cross section on the line 4—4 on Fig. 1 looking toward the front; Fig. 5 is a detail in vertical section on the plane indicated by the line 5—5 on Fig. 2 showing my safety mechanism in active position; Fig. 6 is a fragmentary side elevation illustrating the relative position of parts of my safety mechanism after a key has been returned to normal position but before the die head has returned.

I will first describe so much of the Chisholm machine as is concerned with my invention. The frame of the machine comprises a bed plate 10 and numerous standards or brackets mounted thereon. The keyboard is located at the front of the ma-

chine above an extension of the bed plate and consists of suitable finger pieces 20 having rearwardly extending levers 21. At the rear of the key levers is the reciprocating die head 30 mounted to move laterally in either direction from a central position of rest and carrying die blocks 40 and 41 in cooperating pairs slideable toward and from each other and having respectively male and 10 female dies on their adjacent ends.

Near the rear of the machine are two solenoid magnets (one of which is shown at 60) which operate a common core bar 61 connected by a linkage system 62 with the die head. Above each bank of key levers is a horizontal rod 65, each of which is carried by the rear end of an intermediately pivoted lever 66. The forward end of each lever carries a downwardly extending rod 20 67, which when depressed closes a pair of contacts 68 forming the terminals of a circuit to the corresponding solenoid magnet.

It results from the mechanism just described, that when a key in the right hand bank is depressed the corresponding circuit is closed to energize that magnet, which pulls the die head toward the right until latch mechanism carried therewith engages the rear end of the actuated key lever. Similarly when any key in the left hand bank is depressed, the adjacent lever 66 closes the circuit through the other solenoid magnet which draws the die head toward the left.

The die head when moved by one of the solenoid magnets becomes automatically locked in its selected position by means of a latch movable with the die head. This latch comprises a traveling block or carriage 70 which carries a pair of plungers 71 with 40 inclined lower faces, and a pair of abutments 72, each comprising an L-shaped end on a bar 73, slidably mounted in the block and restrained against inward movement by a compression spring 74. Accordingly, as the carriage approaches a raised key lever, the beveled lower face of the plunger 71 rides over the top edge of the key lever and drops beyond it, then the abutment engages the side of the key lever. The spring allows a slight 50 further movement of the carriage, whereby the same is gently brought to rest, the spring then pushing the carriage so that the same is held accurately in place with the abutment on one side of the raised key lever and the plunger on the other side.

The dies 40 and 41 preferably each have a plurality of characters on their faces and either horizontal row of characters is selected by moving the die head vertically, by a shift mechanism, not shown. The die head is shown as equipped with rollers 31 which ride on a horizontal guide bar 33 which is normally stationary but may be raised by shift mechanism to determine which face of 60 the dies shall be opposite the intermediate

strip to be embossed. On account of this shift movement of the die head, the latch carriage 70 which travels horizontally with the die head is independent as far as vertical movement of the latter is concerned. This 70 is effected by guiding the carriage by rollers 75 extending into a horizontal channel shaped frame member 76, while a vertical gib 77 connects the carriage with the die head. 75

The die head rides on the shiftable bar 33 mentioned and has also a rearward portion 35 around a stationary bar 36 upon which are a pair of compression springs 37 tending to center the die head. The die head is also 80 provided with rollers 39 bearing on opposite faces of the frame bars 110 and 111. The dies 40 and 41 are preferably held in withdrawn position by the fingers of springs 43 carried by brackets 44 on the die head. 85 The drawings also show a pair of sheering dies 46 and 47 operating to cut off the embossed portion of the ribbon.

In front of the die head and in the rear thereof located centrally of the machine are pairs of plungers 80 which are adapted to be engaged by abutment pins 81 on a pair of pivoted vertical levers 82 and 88, the lower ends of these levers carry rollers 83 engaging double crown cams 84 on a shaft 85. 95 This shaft is adapted to be connected by a clutch 96 with a continuously driven pulley 97.

Overlying the plungers 71 is a pivoted bail 90 which is connected by a link 91 to a bell crank 92 which operates a rod 93 extending in front of and normally stopping a member 98 of the clutch. The clutch rod 93 is normally drawn into operative position by the spring 95. 100

It results from the above described mechanism, that whenever the die head comes to position, the corresponding plunger 71 rising from engagement with the key lever raises the bail 90, pulls up on the link 91, swings the bell crank 92 and withdraws the rod 93 from the clutch, thereupon the clutch goes into engagement and the power rotates the shaft 85 which through the cams and levers, forces inwardly the two plungers 80. The selected dies at that time are directly between these plungers and thus are caused to emboss the interposed ribbon. 110 115

The ribbon as shown at A, is originally a flat strip of metal coming from a reel (not shown) and passing between a pair of feed rollers, one of which is shown in Fig. 3 at 100. These rollers are periodically actuated to feed the strip a distance of one character and at the same time flange the edges of it to give it a channel shape. Such channel shaped ribbon is guided by a horizontal rib on the lower portion of the frame plate 110 and the adjacent face of the cooperating frame plate 111. These frame plates are 120 125 130

cut away directly between the plungers 80 so that the positioned dies may move through this gap and emboss the ribbon.

The forward embossing lever 88 is rigidly mounted on a rock shaft 89, and this shaft carries at its end a rock arm 101 which is connected with a lever carrying a pawl 102 operating a ratchet 103 on the shaft 104 of the ribbon advancing roller 100. Thus, on the back stroke of the embossing levers, the ribbon is advanced one character space.

When the space key is actuated, it is necessary to advance the ribbon but not necessary to move the die head. Accordingly, in the Chisholm machine, the space given key 120 carries a latch 121 which engages with the bell crank 92 and swings it to withdraw the rod 93 from the clutch, causing the embossing levers to swing. At this time, the plungers are opposite a clear space between the dies in the die head which are in two groups as shown in Fig. 3, so that no embossing action takes place. On the return stroke of the embossing arms the rock shaft 89 of the arm 88 through the mechanism described feeds the ribbon.

To lock the die head normally in its central position, the Chisholm machine provides a pair of levers 130, each of which carries at its upper end a horizontal bar 131 behind the die head and at its lower end a universal bar 132 overlapping the rear ends of the key levers of the corresponding bank. The die head carries a vertical gib 135 which lies normally between the bars 131 of the two center lock levers. Now, when a key is depressed in the right hand bank, the corresponding bar 131 is withdrawn from engagement with the die head and it is allowed to move toward the right, and the corresponding action toward the left hand takes place when a key in the left bank is depressed. When the key actuated returns to normal position following the embossing operation, the die head travels back to position with its gib sliding along the face of the bar 131 on that side and comes to rest as this gib clears that bar 131 and engages the end of the other bar 131, thereupon the released bar swings forward into place by means of a spring 136 connected to a pin 137 on the lever and the die head is locked in central position. The rearward limit of the stroke movement is controlled by the adjustable stop 138, Fig. 1.

As soon as a key is depressed, the elevated rear end is retained in that position by means of the universal hooked bar 140 swung by a spring 141 so that it engages beneath a tooth 23 on the key lever and this rear end remains elevated until after the embossing is completed. On the return stroke of the forward embossing lever 88, a latch member 142 thereon engages the upper end of a rocking member 143 which carries the universal bar

140 and withdraws it from the tooth 23 and at the same time an arm 145 projecting from this rocking member engages the rod 65 and forces it downwardly, depressing the raised rear end of the key lever, bringing the latter to normal position.

Beneath the key levers is a transverse train of balls 150 having an aggregate available clearance only slightly greater than the width of one key lever, with the result that whenever any key lever is depressed no other key lever may be depressed until the first lever has returned to normal position. The same frame member which supports the train of balls may carry a transverse rod 152 on which springs 153 tending to raise the key levers are anchored.

It will be seen after the return of the key lever to normal position, there is a slight interval before the die head reaches its central position and it is during this interval that occasionally a very rapid operator has struck a second key in the operation of the Chisholm machine before the die head returned to position. As heretofore stated, it is the object of my invention to prevent striking a second key in the same bank during this interval, and it has been necessary to give this description of the Chisholm machine in order that my mechanism, preventing such inadvertent operation which will now be described, may be readily understood.

As heretofore explained, the rocking lever 66 which was swung (forward end down and rear end up) whenever a key in the associated bank was depressed is returned to initial position at the completion of the embossing stroke by reason of the withdrawal of the latch 140 from the key tooth 23, by the arm 145 engaging the rod 65 and the spring 69 acting upwardly on the forward end of the lever. My attachment includes a rearwardly extending bar 160 rigidly secured to the lever 66 and carrying near its rear end a slideable latch dog 161 mounted in a double arm bracket 162 on the lever 160 and pressed toward the rear by a spring 163. This latch dog cooperates with a downwardly extending arm 165 rigid on the end of the rock shaft 166 on which the corresponding center lock lever 130 is mounted.

It will be noticed that there is some clearance between the underface of the overhanging flange of the universal bar 132 and the upper edge of the rear ends of the key levers. When a key is struck, the latch dog 161 rises during the slight interval while this clearance is being taken up sufficiently to stand in front of the arm 165, and thereafter as the key lever movement continues the arm 165 bearing against the latch dog presses it forwardly so that the parts come into the position shown in Fig. 5. Now, as soon as the forward embossing lever 88 returns to its initial position following the embossing

stroke and thereby releases the key which was active and results in the return of the lever 66, the bar 160 is swung down to normal position, whereupon the latch dog 161 springs beneath the forwardly overhanging arm 165 as shown in Fig. 6.

The arm 165 is held in the position shown in Fig. 6, by the rearward canting of the lever 130 by reason of the die head engaging the center lock bar 131. So long as the center lock lever retains this position, no key may be depressed for the arm 165 standing over the latch dog holds the bar 160 down and thereby holds the lever 66 with its rod 65 holding down the keys of that bank. Soon after the die head returns to central position, the spring 136, acting on the center lock lever returns it to normal position, which causes the arm 165 to clear the latch dog, the parts thus coming in position shown in Fig. 1. This frees the keys for action.

It will be seen that the mechanism above described prevents the actuation of any subsequent character key after an actuated key of that bank has been released until the die head has reached its central neutral position. It will be remembered that the Chisholm machine is provided with means preventing the actuation of more than one key at a time, and accordingly the difficulty cured by my mechanism arises only if a key is struck during that very short interval which exists between the return of one key and the return of the die head to neutral position.

When the Chisholm machine is equipped with my mechanism there is no danger of the operator inadvertently pressing a second key too quickly after the release of the first key. The operator may accordingly operate at the maximum speed, and when he finds a key locked he simply retains his finger thereon during the short time that elapses until the key will respond to his pressure.

I have described the operation of the latch dog with reference to the left hand bank of keys. It is to be understood that another one of these arms 160 on the other side of the machine is secured to the other lever 66 and operates on the other center lock lever, in the manner already described, as illustrated by Fig. 2.

Since the space key does not actuate either of the levers 66, I provide an additional bar 170, pivoted on the same center as the levers 66 and drawn by a spring 171 against the underside of the space key lever. This bar 170 extends rearwardly to a position which is normally just in front of the center lock arm 165 and just beneath the plane of its lower edge. Now, whenever the die head is out of neutral position, the arm 165 overhangs the bar 170 as shown in Fig. 5, and the space key cannot be actuated. As soon however, after the die head has returned to central position, the arm 165 is withdrawn

from above this bar 170 as shown in Fig. 1, and the space key is free for action. This mechanism accordingly prevents inadvertent actuation of the space key during that interval when such key is otherwise released, and when its actuation might result in the plungers engaging the dies and effecting improper embossing and perhaps injury to the dies or plungers.

It should be noticed that my mechanisms preventing actuation of a subsequent key apply to the two banks independently, so that the actuation of the key in one bank does not prevent a key in the other bank being actuated immediately after the first key is released. This is permissible since such other key necessarily acts on the die head after it has returned to its central position of rest and passes beyond that position in the other direction. Accordingly, it is immaterial if the operator presses the key in the other bank after the first key has been pressed and before the die head has returned. My locking mechanism does not delay the actuation during such interval.

Having thus described my invention, I claim:

1. In an embossing machine having a cycle of operations initiated by the actuation of a key, the combination of a keyboard, a set of dies, means for holding material to be embossed thereby, there being a neutral position of the dies relative to said material, means for changing and restoring the juxtaposition of the dies and material, the keyboard having finger keys adapted to actuate the last mentioned means, means for restoring an actuating key before the cycle of operation is complete and means for preventing the actuation of a subsequent key, until the neutral position of the dies relative to the material is restored.

2. In an embossing machine having a cycle of operations initiated by the actuation of a key, the combination of a keyboard having finger keys, male and female embossing dies, means for holding material to be embossed, there being a normal position of rest of the dies and material, means for changing the relative position of the dies and material and for restoring such position under the control of an actuated finger key, means for locking such key, means for releasing such key before the cycle of operation is completed and means for preventing the actuation of a subsequent key until the normal position of the dies and material, relative to each other, has been restored.

3. In an embossing machine, the combination of a movable die head carrying embossing dies and having a normal position of rest, mechanism for moving said die head from said normal position, a keyboard having keys for determining the position to which said die head is moved, mechanism for

restoring an actuated key and thereafter restoring the die head to normal position, and mechanism for preventing the actuation of a subsequent key until the die head has been restored.

4. In an embossing machine, the combination of a movable die head carrying embossing dies having a neutral position, a keyboard, mechanism controlled thereby for 10 positioning the die head, mechanism for automatically operating a selected die consequent upon the die head coming to position, means for locking an actuated key, means for releasing such actuated key, means for 15 thereafter returning the die head to neutral position, and mechanism for preventing the actuation of a subsequent key until the die head has returned to neutral position.

5. In an embossing machine having a 20 cycle of operations initiated by the actuation of a key, the combination, with embossing mechanism, of a keyboard for controlling the same, means for restoring an actuated key before the cycle of operation is complete, and means for preventing the actuation of a subsequent key until a preceding key is restored, and means for preventing actuation of a subsequent key after a preceding key is restored but before the cycle 25 of the machine is completed.

6. In an embossing machine, the combination of a movable die head, a plurality of keys, mechanism control thereby to move the die head from a neutral position of rest 30 and thereafter returning to such position, means for locking an actuated key, means for releasing such actuated key before the die head has returned.

7. In an embossing machine having a 40 cycle of operations initiated by the actuation of a key, the combination with a keyboard, of embossing dies actuated thereby, means for locking an actuated key until after the embossing action has taken place and then 45 releasing it before the cycle of operation is complete, and means for preventing the actuation of a subsequent key during the interval between the release of the first key and the completion of the cycle of operation.

50 8. In an embossing machine having a cycle of operations initiated by the actuation of a key, the combination with embossing dies, a plunger mechanism for moving them, a keyboard for causing coaction between the 55 plunger mechanism and selected dies, means for locking an actuated key until after the plunger mechanism has acted, and means for releasing an actuated key before the cycle of operation is complete.

60 9. In an embossing machine, the combination of a movable die carrier having a neutral position, means for moving the carrier from such neutral position and means for returning it thereto, a plunger mechanism 65 for actuating the dies, a keyboard, mech-

anism actuated thereby and having a movement independent of the movement of the actuating key for moving the die carrier to the position determined by the key actuated, whereby dies corresponding to such key are 70 caused to register with a plunger mechanism, and means for locking the keyboard against subsequent actuation of a key in that bank until the die head has returned to neutral position.

75 10. In an embossing machine, the combination of a reciprocating die carrier having a position of rest, key actuated mechanism having a movement independent of the movement of the actuated key for moving the die carrier intermittently from such position of rest, a keyboard having such actuating keys controlling the position to which the die carrier is moved, and means for locking the keyboard against subsequent actuation of a key in that bank until the die head has returned to neutral position.

80 11. In an embossing machine having a cycle of operations initiated by the actuation of a key, the combination of embossing dies, 90 a keyboard arranged in two banks, one bank controlling relative movement of the dies and material to be embossed in one direction and the other in the other direction, and means whereby, when any key has been actuated, no other key in that bank may be actuated until the cycle of operation is completed, means for locking an actuated key and means for releasing such actuated key in advance of the completion of the cycle of 95 operation.

105 12. In an embossing machine having a cycle of operations initiated by the actuation of a key, the combination of a reciprocating die head carrying embossing dies, said die head having an intermediate position of rest and being adapted to move in either direction therefrom, mechanism for so moving the die head, a keyboard arranged in two banks, one bank controlling movement in 110 one direction and the other in the other, and means whereby when any key is actuated, no other key in that bank may be actuated until the die head has returned to neutral position, means for locking an actuated key and 115 means for releasing such actuated key before the cycle of operation is complete.

120 13. In an embossing machine having a cycle of operations initiated by the actuation of a key, the combination with an embossing mechanism of a keyboard for controlling the same, locking mechanism to hold the embossing mechanism in neutral position, means whereby any of a plurality of keys may release such locking mechanism and 125 means for restoring an actuated key in advance of the completion of the cycle of operation.

130 14. In an embossing machine, the combination of embossing dies, means for hold-

ing material to be embossed, a key-board, mechanism actuated thereby for positioning the dies with reference to the material, a lock for preventing such positioning movement, 5 means whereby any of a plurality of keys may move said lock to released position, and a key lever locking mechanism operable by each of said keys and adapted to be blocked in its releasing movement by the embossing 10 lock when the latter is in its abnormal position.

15. In an embossing machine having a cycle of operations initiated by the actuation of a key, the combination of a movable die head, mechanisms for moving it from a position of rest to various active positions and for returning it therefrom, a lock for the die head, a plurality of keys any of which may release the lock and actuate 20 the die head, means for restoring an actuated key before the cycle of operation is complete, and mechanism controlled by such lock to prevent the actuation of a subsequent key until the die head has returned.

25. 16. In an embossing machine, the combination of a reciprocable die head, a lock adapted to hold it in neutral position, a plurality of keys any of which may release the lock, and latch mechanism coacting with the 30 lock preventing the actuation of a subsequent key until the lock has returned to locking position.

35. 17. In an embossing machine, the combination of a reciprocable die head, a center lock adapted to hold it normally in central position, a plurality of keys in two banks, mechanism whereby any key in the bank may release the center lock sufficiently to allow movement of the die 40 head in any direction, and mechanism coacting with the center lock preventing actuation of a subsequent key in the same bank until the center lock has returned to locking position.

45. 18. The combination of a movable die carrier, a lock therefor, a plurality of keys any one of which may release the lock, a member movable by any of said keys and having a latch dog coacting with lock in 50 a manner not to interfere with the operation of the lock, and mechanism controlled by the latch dog for preventing the actuation of a subsequent key until the lock is returned.

55. 19. The combination of a movable die head having a position of rest, a lock having a member adapted to hold the die head in such position, a keyboard having keys cooperating with said member to move it to release the die head for movement, a spring pressed 60 latching dog for said keys, means for moving it into abutting position with means carried by the locking member whereby the spring is constrained as the key operation is completed, and means for moving said 65 latch dog away from the locking member

into a position where it is blocked thereby when the key is returned.

20. The combination of a reciprocating die head having a central position of rest, a center lock having a pair of members 70 adapted to hold the die head in such central position, a keyboard having keys arranged in two banks, each bank cooperating with one of said members to move it to release the die head for movement in that direction, 75 a spring pressed latching dog for each bank of keys, means for moving it into abutting position with means carried by one of the center locking members whereby the spring is constrained as the key operation is completed, and means for moving said latch dog away from the center locking member into a position where it is blocked thereby when the key is returned, thereby holding all of the keys in that bank against subsequent 85 movement until the center lock member is returned.

21. The combination with a movable die head having embossing dies and having a normal position, a locking lever carrying a 90 bar extending parallel with the direction of movement of the die head and coacting with the die head in its various positions other than its neutral position, said locking member coacting with a bank of keys 95 whereby any key in the bank may release said member, means for thereupon causing actuation of the die head along the released locking member whereby the latter may not return to normal position until the die head 100 has returned to normal position, and a latching mechanism coupled with the keys and coacting with such locking member and adapted to prevent the actuation of a subsequent key until the locking lever has re- 105 turned to locking position.

22. The combination with a reciprocating die head having embossing dies, a pair of center lock levers each carrying a bar extending parallel with the direction of movement of the die head and coacting with the die head in its various positions other than its neutral position, each center lock member overhanging a bank of keys whereby any key in the banks may release its center lock member, means for thereupon causing actuation of the die head in contact with the bar of the released center lock member whereby the latter may not return to normal position until the die head has returned to normal position, and a latching mechanism coupled with the keys and coacting with such center lock member and adapted to prevent the actuation of a subsequent key until the center lock has returned to locking position. 110 115 120 125

23. In an embossing machine, the combination of a reciprocating die head having a central position of rest, the keyboard arranged in two banks, mechanisms actuated 130

- by keys in the respective banks for moving the die head from the central position in one direction, mechanism for locking it in a position determined by the key actuated, mechanism for then effecting the embossing operation and releasing the key, a pair of center lock levers each adapted to be actuated by any key in the corresponding bank and serving to release the die head from its normal position of rest for movement in one direction, means for preventing the return of the center lock lever until the die head has returned, and a latch mechanism operated by any key in the bank and coacting with the center lock mechanism to prevent the actuation of a second key in that bank until the die head has returned.
24. In an embossing machine, the combination of a reciprocating die head having a central position of rest, the keyboard arranged in two banks, mechanisms actuated by keys in the respective banks for moving the die head from the central position in one direction, mechanism for locking it in a position determined by the key actuated, mechanism for then effecting the embossing operation and releasing the key, a pair of center lock members each adapted to be actuated by any key in the corresponding bank and serving to release the die head from its normal position of rest for movement in one direction, means for preventing the return of the center lock member until the die head has returned, and a latch mechanism comprising a spring pressed latching dog on a bar movable with any key lever of that bank, and coacting with an arm movable with the corresponding center lock member, said latching dog having its spring constrained when the center lock is released, and mechanism for releasing an actuated key and returning the dog to a position where it is blocked by the center lock whereby subsequent actuation of a key is restrained.
25. The combination of a reciprocating die head having a normal position, character keys for controlling the movement of the die carrier from its normal position, mechanism initiated by such keys for moving the dies to effect the embossing, a space key which feeds the material without causing embossing, mechanism for returning the die head
- to normal position and mechanism for preventing the actuation of the space key until the die head has returned to normal position, said mechanism comprising a locking device for the die head held out of normal position when the die head is in another position than in its position of rest, and key locking mechanism connected with various keys and adapted to be blocked by such locking mechanism when in such released position.
26. In an embossing machine, the combination with embossing dies, of character keys for controlling the mutual presentation of the dies and material to be embossed, mechanism initiated by such keys for moving the dies to effect the embossing, a space key, mechanism actuated thereby for operating the die moving mechanism and for feeding the material at a time when no die is in position to operate, and mechanism for preventing the actuation of the space key until such actuation would not interfere with the dies.
27. In an embossing machine, the combination with a movable die carrier having a normal position, of character keys for controlling the movement of the die carrier from its normal position, mechanism initiated by such keys for moving the dies to effect the embossing, a space key which feeds the material without causing embossing, mechanism for returning the die head to normal position and mechanism for preventing the actuation of the space key until the die head has returned to normal position.
28. The combination of an intermittently movable die head having a position of rest, a keyboard for controlling the active position of the die head, and mechanism for preventing the actuation of a subsequent key of the keyboard comprising a locking device for the die head held out of normal position when the die head is in another position than in its position of rest, and key lever locking mechanism connected with various keys and adapted to be blocked by such locking mechanism when in such released position.

In testimony whereof, I hereunto affix my signature.

PETER M. COLQUHOUN.
